UNITED STATES PATENT OFFICE.

JOHN J. HAYES, OF GREEN POINT, NEW YORK.

DESIGN FOR A PHOTOGRAPHIC HEAD-REST.

Specification forming part of Design No. 6,197, dated October 8, 1872.

To all whom it may concern:

Be it known that I, J. J. HAYES, of Green Point, in the county of Kings and State of New York, have invented a Design for a Photographic Head-Rest, of which the following is a specification:

The nature of my design is fully represented in the accompanying photographic illustration, to which reference is made.

A represents the base, and B the column standing thereon. The surfaces of the base are made smooth, and the edges of said surfaces are, as a rule, straight lines. The objects attained by this construction are, much greater facility in the casting, much better and smoother castings, and it requires much less paint in finishing in consequence of the fine surface obtained. The column is octagonal in

form, encircled by three or more rings, the lower part being larger than the upper, and at the part adjoining the base the octagonal form is further carried out.

The main ideas sought to be embraced are, the octagonal column and the smooth flat surfaces, as this will be the distinguishing characteristic from those heretofore in use, they being made with fluted columns, and profusely decorated with scroll-work, vines, leaves, &c.

What I claim as my invention is—

A design for a photographic head-rest, ornamented substantially in the manner as above described.

JOHN J. HAYES.
